(57) **CLAIM**

The ornamental design for a safety latch installation tool, as shown and described.

DESCRIPTION

FIG. 1 is a rear perspective view of a safety latch installation tool showing our new design according to a first embodiment;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view thereof;

FIG. 9 is another front perspective view thereof, showing an example latch for environment;

FIG. 10 is a rear perspective view of a safety latch installation tool showing our new design according to a first embodiment;

FIG. 11 is a rear elevation view thereof;

FIG. 12 is a front elevation view thereof;

FIG. 13 is a right side elevation view thereof;

FIG. 14 is a left side elevation view thereof;

FIG. 15 is a top plan view thereof;

FIG. 16 is a bottom plan view thereof;

FIG. 17 is a front perspective view thereof; and,

FIG. 18 is another front perspective view thereof, showing an example latch for environment.

The dashed broken lines in the figures illustrate portions of the safety latch installation tool and environment that form no part of the claimed design.
